CLAIM

We claim the ornamental design for a portion of a display screen with a graphical user interface, as shown and described.

DESCRIPTION

FIG. 1 is a front view of a portion of a display screen with a graphical user interface showing a first embodiment of the new design; and,

FIG. 2 is a front view of a portion of a display screen with a graphical user interface showing a second embodiment of the new design.

The broken line positioned around the portion of a display screen with graphical user interface illustrates portions of the display screen with graphical user interface that form no part of the claimed design.
